UNITED STATES PATENT OFFICE.

JOHN C. KONRAD, OF NEW YORK, N. Y., ASSIGNOR TO CLARENCE
WAINRIGHT WOOD, OF SAME PLACE.

DESIGN FOR A BODY FOR DELIVERY-WAGONS.

SPECIFICATION forming part of Design No. 28,750, dated May 31, 1898.

Application filed February 19, 1898. Serial No. 670,976. Term of patent 7 years.

To all whom it may concern:

Be it known that I, JOHN C. KONRAD, a citizen of the United States of America, and a resident of the borough of Manhattan, in the city of New York and State of New York, have invented and produced a new and original Design for a Body for Delivery-Wagons, of which the following is a specification, reference being had to the accompanying drawing, forming part thereof.

The figure of the drawing is a side view of the body of a delivery-wagon, showing said new and original design.

The leading or material feature of the present design is the shape or configuration of the side of the body at its front edge, as represented in the drawing and hereinafter described.

The general outline of the wagon-body as viewed in said figure comprises a front roof edge 1, rounded above, rounded rear corners 2 and 3, a rounded corner 4 at the rear of the arch 5 beneath the seat, an ornate shape of this arch including nearly vertical sides, a nearly flat crown, and pointed projections at its haunches, a rounded corner 6 at the front of said arch, a foot-rest 7, inclined in front, where it supports the dashboard 8, and horizontal in rear of its inclined portion, a line-of-beauty curve 9 in front of the seat portion, a vertical front edge portion 10 next above, and a curve 11 and horizontal roof-line 12 extending to said front roof edge 1. Raised border members 13, 14, and 15, conformed to

the lateral edges of the roof and to the back and bottom, respectively, and like border members 16, 17, and 18, conformed to said arch 5, line-of-beauty 9, edge portion 10, and curve 11, together with corner connections 19, 20, and 21, embellished by inwardly-projecting bilabiate ornaments, inclose a large panel *a* of irregular outline. Said shape or configuration of the side of the body at its front edge includes, with said line-of-beauty curve 9, vertical front edge portion 10, and curve 11, and the said border members 17, 18, and 19, an inwardly-projecting spur 23 at the upper end of said border member 17, and a curvilinear raised border member 24, which, together with a portion of said border member 18, incloses a side opening *b* of an irregular oval shape, the raised border members at the front edge of the side, including said spur 23 and border 24, forming an ornamental "P" in general outline. An oval lamp-window 55 within said panel *a* is represented at *c*, a penciled border-line on said panel at *d*, and a C-shaped scroll within said opening *b* at 25.

Having thus described said design, I claim as new and original and desire to patent under this specification—

The design for the body of a delivery-wagon, substantially as shown and described.

JOHN C. KONRAD.
